UNITED STATES PATENT OFFICE.

JACOB BUCHLI, OF WINTERTHUR, SWITZERLAND.

HIGH-PRESSURE STEAM BOILER.

Application filed June 29, 1925, Serial No. 40,297, and in Germany February 9, 1925.

The present invention relates to improvements in high pressure water-tube boilers having an upper drum and an element for bounding the rear end of the firebox.

5 The rear wall of the fireboxes of water-tube boilers has been formed in various ways, for instance by means of tube elements, or by a brick wall and other means, however, besides other disadvantages these 10 arrangements present the drawback that they do not in most cases permit to utilize a normal fire-door.

The subject matter of the present invention is a high pressure water-tube boiler 15 having an upper-drum and a rear wall of the firebox within which a ring shaped member is shrunk to the upper drum and is provided in its lower part with a plurality of bores extending in the upward direction. 20 This member is united by welding to a hollow body arranged below it, which hollow body forming the rear wall of the firebox is provided with flat walls stiffened by stay tubes and the interior of the hollow body is 25 in communication with the upper drum by the bores in said ring shaped member.

With this rear wall tight joints also to the upper drum are obtained as well as an increase of the heating surface owing to the 30 circulation of water within the hollow body and it further permits the utilization of a normal fire-door.

A constructional example of the subject matter of the present invention is illustrated 35 in the accompanying drawings, in which:

Fig. 1 shows the upper drum and the rear wall of the firebox in a vertical cross-section in the left hand side of Fig. 1 and in a front view in the right hand side of Fig. 1 and

40 Fig. 2 shows the water-tube boiler and the rear wall of the firebox in a vertical longitudinal section.

To the upper drum 1 the member 2 which is ring shaped in its upper part is shrunk 45 and to the member 2 the hollow body forming the rear wall of the firebox is welded along the seam 4. The hollow body may for instance consist of two halves 3 and 3' having flat walls dished in along their circumference and welded together at the seams indicated in Fig. 2 at 4' and 4''. An opening 5 for the fire door is provided in the hollow body 3 and the flat walls are stiffened 50 by the stay tubes 6 expanded into the walls 3 and 3'.

In the member 2 bores 7 pointing in the

downward direction are provided which communicate at one end with the interior of the hollow body 3, 3' and at their upper end with the bores in the upper drum 1. To 60 tighten the bores 7 with regard to the bores in the upper drum 1 tubes 8 are expanded in the upper part of the bores 7.

An insulating layer 9 is provided at the outside of the hollow body 3, 3' and is covered by sheet metal 10. 11 denotes the water tubes arranged inside the firebox and forming the walls of the latter as disclosed in my Patent No. 1,576,807, dated March 16, 1926.

I claim:

1. In a high pressure water tube boiler, in combination, an upper drum, and a rear wall for the firebox comprising a member embracing said upper drum and shrunk to the latter and provided with bores in its lower part registering with bores in said upper drum, and a hollow body consisting of two connected halves fixed to said member and having flat walls stiffened by stay tubes, the bores in said member registering with bores in said hollow body.

2. In a high pressure water tube boiler, in combination, an upper drum, and a rear wall for the firebox comprising a member embracing said upper drum, shrunk to the latter and provided with bores in its lower part registering with bores in said drum and having tubes expanded in said bores to prevent leakage at the junction of said bores and a hollow body consisting of two connected halves fixed to said member and having flat walls stiffened by stay tubes, the bores in said member registering with bores in said hollow body.

3. In a high pressure water tube boiler, in combination, an upper drum, provided with bores in its lower part and a rear wall for the fire box comprising a member embracing said upper drum, shrunk to the latter and provided with bores in its lower part registering with the bores in said upper drum, and having tubes expanded in said bores to prevent leakage at the junction of said bores, and a hollow body consisting of two halves welded together and welded to said member and having flat walls stiffened by stay tubes, the bores in said member registering with bores in said hollow body.

In testimony whereof, I have signed my name to this specification.

JACOB BUCHLI.
